PAPER BALER

Thomas E. Wykes, Grand Rapids, Mich.

Application February 18, 1942, Serial No. 431,359

6 Claims.

(Cl. 100—19)

This invention relates to a packager or baler particularly adapted for compressing and packing waste paper in a special carton therefor to greatly reduce the space which the paper when free occupies, the carton being closed and sealed after the paper has been compressed and when the carton is full, thereby greatly facilitating the collection and handling of waste paper, particularly in households.

It is a primary object and purpose of the present invention to produce a device of the character indicated which can be manufactured and sold at low cost, which is readily operated by practically everyone, and which is of a novel construction and is novel in its operation in connection with an especially constructed carton usable therewith for the attainment of simple, rapid and effective compressing of waste paper into small compass, and carton enclosing and sealing it in its compressed state for easy and effective handling and delivery.

An understanding of the invention and of a novel preferred construction embodying the same may be had from the following description, taken in connection with the accompanying drawings, in which,

Fig. 1 is a perspective view of the paper baling device of my invention.

Fig. 2 is a plan view thereof.

Fig. 3 is a vertical section from front to rear, substantially on the plane of line 3—3 of Fig. 4, through the baler and carton therewithin, and

Fig. 4 is a vertical section at right angles to the plane of the section shown in Fig. 3, taken substantially on the plane of line 4—4 of Fig. 1.

Like reference characters refer to like parts in the different figures of the drawings and the section views are taken looking in the direction indicated by the arrows.

The baler includes an open frame structure in which the special carton used therewith is releasably held and supported. The back of the frame is made of a plurality of spaced apart bars 1, rectangular in cross section permanently connected with similar vertical tie bars 2 at their outer sides. This back of the baler is adapted to be rigidly secured at the front side of a vertical post 3 resting upon the floor of a room or basement for example, above which the post extends. The post is located substantially midway between the ends of the bars 1 and between the two vertical tie bars 2. Above the upper bar 1 of the back of the baler construction a block 4, the width of which may be equal to the width of the post and the thickness of which preferably

will approximate the bars 1, is permanently secured as shown.

The ends of the baler likewise comprise open members consisting of spaced apart horizontal bars 5, similar to the bars 1, connected to an outside vertical tie bar 6. The rear ends of the bars 5 come adjacent the outer ends of the bars 1 and either all or only a part of the adjacent bars 5 and 1 are hingedly connected together by hinges 7. In practice with the back and the ends of the baler including five spaced apart bars 1 and 5, a sufficient hinge connection is provided by connecting two of the bars 1 and 5 together as shown in Fig. 3. Likewise part of the bars 5 at one end of the baler at their front ends are equipped with hooks 8.

The front of the baler consists of two vertical tie bars 9 at the outside to which a plurality of horizontal bars 10, one less than the number of bars 1 and 5, are permanently connected. At one end part of the bars 10, two as shown, are hinged by hinges 7 to the front end of two of the bars 5 at one end of the baler. At the opposite ends of the bars thus hinged, eyes 11 are secured with which the hooks 8 may detachably connect.

Instead of an uppermost bar like the bars 10 extending entirely across as the bars 10 do between the tie bars 9, at the upper end of each tie bar 9 is a section bar 12 which is permanently secured as shown, the inner ends of the sections 12 being separated from each other by a space indicated at 13. In other words, the upper section bars 12 consist of a bar 10 having a central portion removed. Such baler may be readily opened by unhooking the hooks at 8 and moving the end sections laterally and swinging the front with respect to the end member of the baler to which it is hingedly connected.

Within this baler a carton made of paper stock is placed. The carton has a bottom 14, front and rear vertical sides 15 and vertical ends 16 which in practice will extend to between the uppermost bars of these front, back and ends 45 of the baler and the bars next below (Fig. 3). From the ends 16 closing flaps 17, hingedly connected as by scoring, may be positioned vertically as shown in Fig. 3. The flaps 18 extending from the front and rear sides 15 are cut away between their ends providing vertical slots 19 which, at the rear of the carton, extend to the upper end of the rear side 15 but at the front extend farther down or approximately to the upper side of the uppermost continuous bar 10 55 of the front of the baler (Fig. 1).

The carton when thus within the baler and with the upper closing flaps extended is in a position to receive paper loosely dropped in the carton. A presser to compress the paper is provided consisting of a head which may take many forms, but as shown consists of an open frame having three spaced apart bars 20 at its lower side. Two bars 21 transverse thereof and over their end portions permanently connect thereto and a trapezoidal member 22 is above and substantially midway between the ends of the bars 20 and permanently secured therewith, the upper side of the member 22 being in a horizontal plane. Such presser head when placed upon the paper and force supplied thereto packs and compresses the paper.

Above the member 22 is a loose block 23 rectangular in cross section, the height of which preferably is greater than the width and the width greater than the thickness. A handle lever 24 is utilized, its rear end being placed underneath the lower edge of the uppermost bar 1 of the back and resting between its ends on the upper end of the block 23. The free forward end portion of the handle extends in front of the baler for the application of weight, the effect of which is multiplied by the longer arm of the weight receiving end of the lever, thereby heavily compressing the paper. It is evident that the lever 24 passes downwardly through the slots 19 and at its front portion may be forced downward until stopped by the upper bar 10 at the front of the baler. The block 23 when the carton is nearly filled with compressed paper may be turned on an edge to reduce the height between the part 22 and the lever 24 and at a still further stage placed on its side to still further reduce such height.

When the carton is nearly full and a release of pressure permits the paper to expand upwardly a portion of the distance that it has been compressed so that it reaches above the upper end of the carton and into the space surrounded by the flaps 17 and 18, the presser head is elevated, in which case the rear end of the handle lever 24 is inserted underneath the lower edge of the block 4. When the carton is full and is to be sealed the flaps 17 and 18 are turned downwardly as far as they will go against the paper. Then, if necessary, the presser head is placed on the outside of the upper flaps, the bar 24 located over the presser head and with its rear end underneath the block 4 and the closing flaps 17 and 18 thus forced to horizontal closing position. In this position they may be partially sealed by a sealing tape in the usual manner through openings in the presser head. The remaining unsealed or unsecured edge portions of the flaps may be more securely sealed if necessary on removal of the presser head.

The simplicity of the invention and the resulting economy in manufacture render this invention particularly available at the sources of waste paper, the individual households where the saving of waste paper in loose form for the lengths of time between collections and removal thereof is disliked by many on account of the nuisance and litter attending and because of the fire hazard accompanying it.

The invention described is very effective and of a simple and economical construction. The handling of waste paper is greatly facilitated by the invention. It results in very much greater recovery of waste paper. The carton and its special construction involving the slots 19 in the

upper end closing flaps are vitally essential for the practical use of the invention and the operation of the presser means used to compress the paper.

5 The invention is defined in the appended claims and is to be considered comprehensive of all forms of structure coming within their scope.

I claim:

1. A construction including a carton having a bottom, vertical sides, upper end closing flaps adapted to extend vertically from the sides of the carton, the front and rear closure flaps being vertically slotted between their ends downward for a distance from their upper edges, said
- 15 carton being adapted to receive material to be compressed therein, means including a presser head and a hand lever for operating same, said lever extending across and being adapted to pass through and transverse the slots in said carton closure flaps to force the presser head downwardly, means around the carton at its sides for holding said sides against outward bulging, and means associated with the last named means for operatively engaging said lever.
2. In a device of the character described, a containing carton having a bottom, vertical sides, end closure flaps at the upper end of said sides adapted to extend vertically upward from the sides of the carton, certain of the closure flaps connected with the sides of the carton being slotted between their ends, a post adjacent which one side of the carton is located, a hand operated lever means connected with said post for engaging the rear end of said lever, a presser head for use within the carton to be engaged by the lever on downward movement thereof to compress material in the carton, said lever being adapted to pass through said slots, and means surrounding the carton at its sides to hold it against outward bulging under pressure, said surrounding means being releasable from said carton for removing the same after it has been filled with compressed materials.

3. In a structure of the class described, a vertical post, a back enclosure member attached to the post, a carton located in front of the back member, said carton having a bottom and vertical sides, and upper end closure flaps adapted to extend vertically from said sides of the carton, said back member extending above the upper end of the rear side of the carton, the closure flaps attached to the front and rear sides of the carton being vertically slotted a distance to approximately the upper edges of the sides of the carton and the front side of the carton being slotted to form a downwardly extending continuation of the slot in the front closure flap, a hand lever, said back member having an opening for the entrance of said lever, said lever being adapted to pass through said slots, a presser head adapted to be located in the carton and underneath the lever, enclosure sides movably connected to said back member to lie along two sides of the carton, and an enclosure front movably connected to one of said enclosure sides and detachably connected to the other thereof normally located at the front side of the carton, said enclosure front at its upper portion being cut away co-extensively with the slot in the adjacent closure flap to permit downward movement of said lever.
4. A construction containing the elements in claim 3, combined with a block secured to the front side of the post a distance above said back member sufficient for the reception of the rear

end of the lever underneath the block and over the upper edge of said back member.

5. In a construction of the class described, a vertical post, an enclosure back including a plurality of connected spaced apart horizontal bars connected to said post, enclosure ends comprising a plurality of connected spaced horizontal bars hingedly connected to the enclosure back at each end thereof, an enclosure front including a plurality of spaced apart connected horizontal bars hingedly connected at one vertical side at and to the front edge portion of one of said enclosure ends, means for releasably latching said enclosure front at its other vertical edge portion to the front part of the opposite enclosure end, said enclosure back, ends and front defining an enclosure, the upper bar at said front having a section removed substantially midway between its ends, and a carton located within the enclosure

having a closed bottom, vertical sides and end members and upper end closure flaps adapted to be positioned vertically, the flaps attached to the front and rear sides of the carton being vertically slotted, and the front side of the carton being slotted to form a continuation of the slot in the front closure flap, said continuation extending downwardly to the horizontal bar of said front of the enclosure next below the uppermost bar, as and for the purposes specified.

6. A construction containing the elements in combination defined in claim 5, combined with a block permanently secured to the front side of the post above the upper side of the back of said 15 carton enclosure and spaced from the uppermost horizontal bar thereof, as and for the purposes specified.

THOMAS E. WYKES.
